UNITED STATES PATENT OFFICE.

HERBERT W. OWEN, OF DOVER, NEW HAMPSHIRE, ASSIGNOR TO WHITIN MACHINE WORKS, OF WHITINSVILLE, MASSACHUSETTS, A CORPORATION OF MASSACHUSETTS.

SPINNING-MACHINE.

1,161,959.

Specification of Letters Patent. Patented Nov. 30, 1915.

Application filed February 27, 1914. Serial No. 821,544.

To all whom it may concern:

Be it known that I, HERBERT W. OWEN, a citizen of the United States, residing at Dover, county of Strafford, and State of New Hampshire, have invented an Improvement in Spinning-Machines, of which the following description, in connection with the accompanying drawings, is a specification, like letters on the drawings representing like parts.

The invention to be hereinafter described relates to spinning machines for twisting cotton or woolen fibers into yarns or threads, and more particularly to the drawing mechanism whereby the fibers to be twisted together are drawn out and presented to the spinning mechanism.

As well understood by those skilled in the art, the drawing mechanism comprises a series of drawing rolls arranged in pairs between which the fibers to be treated are delivered in the form of light roving to be drawn out or attenuated and delivered for the spinning operation. The action of the drawing rolls attenuates the roving or rovings and by the compression of each succeeding pair of rolls flattens out the fibers, so that as the roving is delivered at the front rolls it is often too weak to withstand the spinning operation. This flattening or spreading of the fibers by the combined pressure and drawing action of the rolls is well understood by those skilled in the art, and is a constant menace to the continuity of the yarn at the front rolls.

With these generally recognized facts in mind, the aims and purposes of the present invention are to provide means whereby the effect of the spreading action of the drawing rolls upon the fiber is largely counteracted, the fibers made to associate and hug more closely together, and delivered at the front rolls in a form best calculated to withstand the strain incident to the spinning operation, all of which will best be made clear from the following description and accompanying drawing of one form of means for carrying the invention into practical effect, it being understood, however, that the invention is not restricted to the particulars shown, but in its true scope is defined by the claims.

In the drawings:—Figure 1 is a view looking at one end of a ring spinning frame

and its drawing rolls showing the present invention associated therewith, some of the parts being in section and unnecessary portions of the spinning frame being omitted; Fig. 2 shows the relation of the drawing rolls, traverse rail, and the present invention, the view being partially diagrammatic in plan to make clear the action of the parts; Fig. 3 is a detached detail in end view of one form of means for carrying the invention into practical effect.

For the purpose of making clear the action and purposes of the present invention, it is herein shown as associated with the drawing rolls of a ring spinning frame, and the fibers to be drawn and spun as formed in two separate rovings; but it is to be understood that the invention is not restricted to either of these conditions.

The frame 1, the wire or thread board 2, the thread guide 3, the ring-rail 4, the stand 5 for carrying the drawing rolls, the drawing rolls themselves, the clearers for the drawing rolls and the traverse rail 6 and their associated relation may all be of any desired character, and, being well understood by those skilled in the art, need no special description herein.

As usual in this class of machines, the back drawing rolls 7 and 8 are rotated to draw the roving or rovings from a source of supply, the middle drawing rolls 9 and 10 are rotated at a somewhat faster peripheral speed than the back rolls, and the front rolls 11 and 12 are driven at greater peripheral speed than the middle rolls, with the result that as the roving passes from the back to the front rolls, it is drawn out or attenuated into its final form for receiving the twist or spin that takes place between the bobbin and the bite of the front drawing rolls. The drawing rolls press upon the fibers as they pass between the rolls, so that the fibers, while being drawn out, are also spread or flattened, thereby weakening the roving with the result that when delivered from the front rolls, the strain upon the roving caused by the spinning action, results in breakage.

The present invention contemplates means to prevent this weakening of the fibrous strand or roving and inasmuch as the fibrous strand or roving is constantly being moved longitudinally of the drawing rolls, said

means is given a movement coincident with that of the fibrous strand or roving as it travels longitudinally of the rolls.

Mounted upon the traverse rod 6 is an arm 13 which projects between the back and middle drawing rolls in the path of travel of the fibrous strand or roving 14, so that as the strand or roving passes from the nip of the back rolls to the nip of the middle rolls, it meets the arm 13, and the fibers thereof which have become flattened or spread out by the action of the back rolls, as indicated at *a*, Fig. 2, are rearranged into more compact relation and caused to hug closely together, so that upon delivery by the front drawing rolls, the roving, now attenuated to the desired extent, is sufficiently compacted to withstand the strain of spinning. The arm 13 for deflecting the roving or fibers may be variously formed and mounted to move lengthwise of the drawing rolls with the roving, and as shown in the illustrated embodiment of the invention, it comprises a guide member 15 having a guide eye 16 for the roving or rovings, and a slotted portion 17 by which the device may be secured to the traverse rail 6, as by the screw 18. Projecting from the guide member 15 is the arm 13 which is given such form, substantially as shown, that it may pass about the back rolls and have its free end extend between the back and middle rolls.

By reference to Figs. 2 and 3, it will be noted that the portion of the arm 13 which acts as the deflector for the roving or fibers, is in direct alinement, substantially with the guide eye 16 through which the roving or rovings pass from the traverse rail to the back rolls, the result being that as the roving travels between the back and middle rolls it is turned or partially turned to one side, as indicated in Fig. 2, whereby the fibers composing the roving which have become flattened or spread out by the back rolls, are now reassembled, compacted, and caused to hug closely together as the roving passes from the back to the middle rolls.

The guide eye 16 in the guide member 15 may conveniently take the place of the old trumpet, and the slot 17 in the guide member 15 provides a convenient means for the adjustment of the guide eye and consequently the arm 13. It may not always be desirable to replace the trumpet by the guide member 15, and in such case obviously the arm 13 may be projected between the back and middle rolls, either from the traverse bar or

any other suitable support which will enable the arm 13 to traverse lengthwise of the drawing rolls with the traverse bar.

Various changes may be made in the details shown as the present embodiment of the invention, and the position of the deflector or arm 13 may be varied, it being preferably placed as close as convenient to the bite between the back rolls.

What is claimed is:—

1. A roving controller comprising a member having a guide eye, an arm extending from said member at one side of the guide eye and having an upwardly bent end, said arm being bent laterally with respect to the guide eye member to position the upwardly bent end of said arm in a vertical plane passing through the guide eye at right angles to the axis of the drawing rolls.

2. A roving controller for spinning machines, comprising a guide member having a guide eye, and a deflecting arm projecting from one side of said guide member and extending to a position opposite to and in a vertical plane passing longitudinally through the guide eye of said controller at right angles to the axis of the drawing rolls.

3. A roving controller for spinning machines, formed of a single piece of material bent to form a guide member having a guide eye and an arm extending from one side of said guide member and having an upwardly bent end, said arm being bent to one side to position the upwardly bent end into a position opposite to and in the vertical plane passing longitudinally through the guide eye at right angles to the axis of the drawing rolls.

4. A roving controller for spinning machines formed of a single piece of material bent to form a guide member having a downwardly opening slot and a guide eye, at the upper portion of said slot, an arm extending from one side of the guide member and having its end bent upwardly, said arm between the said end and guide eye being bent laterally or to one side to position said end in the vertical plane passing longitudinally through the guide eye at right angles to the axis of the drawing rolls.

In testimony whereof, I have signed my name to this specification, in the presence of two subscribing witnesses.

HERBERT W. OWEN.
